DEHUMIDIFIER

Walter Franklin Breen, Lancaster, Pa., assignor
to Hamilton Watch Company, Lancaster, Pa.

Application November 23, 1938, Serial No. 241,951

9 Claims. (Cl. 219—39)

The object of this invention is to provide compressed air which is free from moisture vapor.

Another object of this invention is to provide a neat, convenient, and compact device for dehumidifying air, which device can be easily and conveniently placed on or close to the work bench.

A further object of this invention is to provide an inexpensive device for dehumidifying air, which device can be made substantially entirely from conventional pipe fittings.

Other and further objects will be clearly apparent from the following specifications and from the drawings.

The use of compressed air for various purposes is old. However, as far as is known, compressed air has never been used for the purpose of cleaning articles of production. Also to dehumidify the air before using it to clean articles of production is likewise new. This is especially advantageous in the manufacture of certain devices and instruments where moisture, rust, and corrosion are a major factor to be contended with. Specifically, this invention is especially adapted to be used in the watch industry where the above named factors must be given prime consideration, although it is in no sense limited to the instrument field. However, for purposes of illustration only I will describe the use of my device in the timekeeping field.

As watch movements, instruments, and other articles pass through the different operations in the factory, the dust and dirt which is carried in the air and also which is caused by the operations themselves, accumulate on various parts. To clean these parts, the former practice has been to use a small brush or broom. These brushes cleaned the parts to a certain extent, but quite often the dust and dirt were merely pushed from one location to another and lodged in other crevices. Then too the bristles in even the best brushes come out in time. Inspection of the different operations on exceedingly small parts under these conditions with any degree of accuracy was impossible.

The use of ordinary compressed air to clean watch movements while passing through the various stages of manufacture, would also not satisfy the fine requirements of the watch industry because of the deposition of minute particles of moisture upon the watch parts. These minute particles of water subsequently start the action of corrosion which is fatal to the operation of a timepiece.

One of the inventive concepts in this invention is that of heating the air as it passes through the

pipe, thereby allowing the air to absorb all the existing moisture in it, and also subsequently enabling it to absorb any minute particles of water vapor which had already condensed on the watch parts. This is of increasing importance by reason of many plants and factories being air conditioned in only certain departments. Hence, when sub-assemblies are taken from one department to another there is likely to be an appreciable amount of condensate on the article.

The invention may be clearly understood by referring to the drawings. However, it should be clearly understood that I do not intend that my invention should be limited by the drawings or any description, but only to be limited by the broadest possible scope thereof.

In the drawings:

Fig. 1 is one modification of my dehumidifier showing in detail all the operative elements.

Fig. 2 is a sectional view of a modified form of my device, using conventional pipe fittings for the major portion of the construction.

Fig. 3 is a plan view of the cap shown in Fig. 2.

Fig. 4 is a sectional view of an additional modification.

Fig. 5 is a view of Fig. 4 taken on the line 5—5.

Fig. 6 is a plan view of still a different modified form of my invention.

Fig. 7 is a view of the device illustrated in Fig. 6 showing the internal construction thereof.

Fig. 8 is a view of Fig. 6 taken on the line 8—8.

In Fig. 1 is seen a metal casing 1, which houses the heater element 3. This metal casing is entirely enclosed by asbestos or other heat insulating material. The insulating material is used for the purpose of protecting the user's hands against being burned if the heating assembly is placed on the work table, or to protect the operator's body if the device is placed below the work table. If desired, the metal container itself may be made of heat insulating material, thereby obviating the necessity for the use of the outer insulating casing.

Electric leads 4 are connected to the heating coil and are supplied either with alternating current or direct current. If desired, the leads may be equipped with an adjustable rheostat, to vary the temperature of the air passing through the heating chamber.

For convenience, 5 generically indicates the entire valve assembly and operating mechanism therefor including the foot treadle.

Element 6 indicates a conical shaped valve which is forced into the circular hole of the outlet pipe by means of a spring 7.

Element 8 indicates the rear shank of the valve 6. This rear shank has a groove cut in it around which the bifurcated lug 10 of the handle 9 is positioned. The handle 9 is pivoted to extension 16a, of the pipe 16, by means of pin 11. Element 12 indicates a flexible wire or chain connecting the foot treadle 13 with handle 9, while 14 indicates an extension on treadle 13 which is pivotally connected to a mounting on the floor. If the operator so desires the elements 12, 13 and 14 10 may be eliminated, and the handle 9 operated by hand.

Valve housing 17 is connected to pipe 15 by means of pipe 16 at one end, and to pipe 20 by means of nut 19 and insulation or packing 18 at the other end. Element 21 indicates the pipe 20 which is within the heating chamber 1 and whose outlet leads to cap 22. Over this cap the articles to be operated on are passed in order to be properly cleaned by a strong blast of heated air without the disadvantages of having moisture deposited on the parts. In some instances it may be found desirable to place a sump or a simple complete circular bend in the pipe 15 to prevent any excess moisture from entering the valve housing. 25

Fig. 2 shows a modified form of a dehumidifier in which 5 represents the entire valve assembly including the valve and operating treadle, etc., therefor. Elements 15 and 20 include inlet and outlet pipes similar to those shown in Fig. 1, pipe 30 20 being connected to reducing socket 28 by reducing bushing 28a. The heating element 23 in this modification is inserted within a conventional pipe or nipple 26, which is threaded at both ends. On the inner end of this nipple is threaded a cap 27 which closes the cavity at that end, while the outer end is threaded into a reducing socket 23. Into the last mentioned end of the reducing coupling is screwed a bushing or wire clamp 25 which houses the insulating material, 24, through which the electrical leads 4 pass. This bushing has two upstanding lugs through which is passed a screw element which securely holds the insulating material in position. The reducing socket is in turn fastened on the nipple 29. Elbow 30, reducing bushing 31, nipple 32 and apertured cap 34 are threaded together and attached to nipple 29.

In order that the pipe 32 may dissipate heat more rapidly circumferentially extended fins 33 are cut into its outer circumference, although this feature may be dispensed with. I have found by experiment that nipple 33 will not become nearly as hot if a reducing bushing, such as 31, is used instead of threading elbow 30 and nipple 33 directly together. Apparently much of the heat from nipple 27 and elbow 30 is dissipated by the large head of the reducing bushing instead of passing to the nipple 33. A bushing of insulating material might also be used if desired.

As shown in Fig. 3, apertures 35 extend toward a common center in order that the stream of air may be strongest at this point. The object of having only one aperture at one side is in order that the dirt may be blown away from the 65 operator.

Fig. 4 shows another modification of the dehumidifying devices in which 36 represents the casing which houses the core element 39 which has radially extending fins 45. This core 39 and fins 45 are heated by means of a coil 23, positioned in its central portion. Arms 37 support the core by means of screws 38. The lower end of the central portion of the core is closed by means of metal stopper 46. The leads to the 75

heating element pass through insulation 41, the outer end of which passes through a ventilating aperture 43. These ventilating apertures are positioned in the upper end of the skirt like portion or protecting cover 42. Screws 44 hold protecting cover 42 tightly against the upper end of the casing 36. This protecting cover could also be formed of a series of spaced longitudinal bars.

Arms 37 can be secured by screws, rivets or any other appropriate means to the top of casing 36. Likewise, if desired, the side of casing 36 may be screw-threaded to the top thereof.

In this modification, the valve assembly 5 is positioned above the dehumidifying unit and is positioned adjacent to the nipple 22.

In the modification shown in Figs. 6, 7 and 8, 46 indicates the attaching nut while 49 indicates the passageways which have been drilled out of the solid block of metal 47. In this modification the ends of two of the passageways have been closed by means of metal stoppers 50. The legs of this dehumidifier 50 are removable. The screw 52 holds the heating element which is enclosed in an insulating case 53 within the dehumidifier.

The operation of this device is clearly apparent from an inspection of the drawings. The operator holds the piece which is to be cleaned over the cap 22, and presses the treadle 13 which by means of handle 9 in turn opens the valve 6 and allows the desired quantity of air to pass through the heating chamber. As the air passes through the coiled tube in the heating chamber, it is raised to the desired temperature and no moisture is deposited on the object which it is desired to clean. Further, any moisture already present will be absorbed by the heated air.

The method of installing these devices is also 40 very simple, for example, a hole is bored in the work bench and the upper end of pipe 20 shown in Figs. 1 and 4 and pipe 32 in Fig. 2 is passed therethrough. The nipple 22 and cap 34 are then applied and screwed down flush with the 45 work bench. The small heating and dehydrating apparatus set forth in Fig. 8 is adapted to be placed directly on the work bench.

Features seen in one modification may be readily adapted to other modifications. For example, the valve assembly illustrated in Figs. 1 and 2 could be positioned between cap 22 or 34 respectively and the connecting pipe. Also nipple 26 in Fig. 2 could be formed with fins thereon similar to fins 45, and protective cover 42 shown in Fig. 4 could be fastened to the upper end of nipple 32 to act as additional protection.

It is thus seen that I have invented a simple and entirely practical device for accomplishing the objects of my invention and in which the heating element is entirely enclosed and there is no danger of a particle of heating element being blown by the air into the object to be cleaned, certain parts of which may have been previously cleaned by inflammable substances.

What I claim is:

1. A dehumidifier fabricated almost entirely from conventional pipe fittings and comprising a heating chamber, an air inlet pipe to said chamber, a heating coil in said chamber, a pipe nipple for housing said heating coil and for preventing direct contact between the heating coil and the air to be heated, and an outlet nipple having circumferentially extending heat radiating fins thereon.

2. A dehumidifier fabricated almost entirely

from conventional pipe fitting and comprising a heating chamber, an air inlet pipe to said chamber, a heating coil in said chamber, a pipe nipple for housing said heating coil and for preventing direct contact between the heating coil and the air to be heated, a bushing, an insulated plug in said bushing having apertures therein, leads for said heater passing through said apertures in said insulating plug, an outlet nipple having circumferentially extending heat radiating fins thereon, and an outlet cap, said outlet cap having the apertures therein so positioned that the separate streams of air meet at a common point.

3. A device for drying air in the watch and clock industry comprising a conventional pipe, an air inlet port to said heating chamber, a reducing socket threaded to said pipe, a smaller pipe positioned in said heating chamber, a cap on said smaller pipe, and a heating coil positioned within said smaller pipe.

4. A dehumidifier comprising conventional pipe structure in which a small nipple forming a closed compartment is positioned within a larger nipple, a heating coil in said closed compartment, an inlet and an outlet to said heating chamber, and heat radiating fins circumferentially positioned around said outlet.

5. A dehumidifier comprising conventional pipe structure in which a small nipple forming a closed compartment is positioned within a larger nipple, a heating coil in said closed compartment, an inlet and an outlet to said heating chamber, heat radiating fins surrounding said outlet, and

a cap over said outlet, said cap having apertures therein so constructed and arranged that the fluid passing therethrough meets at a common center.

5 6. A device for drying air comprising a pipe forming a heating chamber, an air inlet port to said heating chamber, a socket fastened to said pipe, a smaller pipe positioned in said heating chamber having a cap on one end, and a heating coil positioned within said smaller pipe.

10 7. A dehumidifier comprising pipe structure in which a small nipple forming a closed compartment is positioned within a larger nipple, a heating coil in said closed compartment, and an inlet to and an outlet from the inside of said larger nipple.

15 8. A dirt remover fabricated almost entirely from pipe fitting and comprising a heating chamber, an air inlet pipe to said chamber, a heating coil in said chamber, a pipe for housing said heating coil, a bushing, an insulated plug in said bushing having apertures therein, and an outlet from said heating chamber.

20 9. A device for removing dirt from articles of manufacture comprising a conventional pipe forming a heating chamber, a fluid inlet port to said heating chamber, a reducing socket secured to said pipe, a smaller pipe positioned in said heating chamber, a cap on said smaller pipe, and a heating coil positioned within said smaller pipe.

25 30 WALTER FRANKLIN BREEN.
